UNITED STATES PATENT OFFICE.

WAYNE RAWLEY, OF PITTSBURGH, PENNSYLVANIA, ASSIGNOR TO BLAW-KNOX COMPANY, OF PITTSBURGH, PENNSYLVANIA, A CORPORATION OF NEW JERSEY.

ANNEALING BOTTOM.

Application filed February 8, 1922. Serial No. 535,103.

To all whom it may concern:

Be it known that I, WAYNE RAWLEY, a citizen of the United States, residing at Pittsburgh, in the county of Allegheny and 5 State of Pennsylvania, have invented a new and useful Improvement in Annealing Bottoms, of which the following is a full, clear, and exact description.

My invention relates to annealing bottoms. 10 Due to the high temperatures to which these structures are subjected, and also to the great changes in temperature, they warp, sag, and, as ordinarily constructed, pull apart and become leaky where the legs are 15 attached to the bottom. This is due to many causes.

I have devised a simple bottom which avoids these and other troubles. My bottom comprises a body member of substantially 20 uniform wall thickness throughout and free from external projections. To this portion is welded any desired number of cylindrical hollow legs having a wall thickness substantially equal to that of the body portion, 25 and also having substantially the same expansion and contraction as that part of the body portion to which they are attached, under given changes of temperature. The metal of the legs is of substantially the same 30 chemical composition as that of the body portion.

By reason of my construction, the bottom is heated up as rapidly as the remainder of the box, so that the material at the bottom 35 of the pack is subjected to the same heat treatment as the other part thereof.

My invention will be better understood by reference to the following description taken in connection with the accompanying drawing forming a part hereof and in which:

Figure 1 is a plan view of a structure embodying my invention;

Figure 2 is section on the line II—II of Figure 1; and

Figure 3 is a perspective view of one of the legs before it is attached to the bottom.

The bottom comprises a body member 1 having a flat bottom portion 2 and an upstanding flange 3 extending around the same. 50 The member 1 may be of any desirable material and of any suitable shape, but is of uniform wall thickness throughout, and free from projections external or internal. Attached to the bottom of the part 2 are legs 55 4. These legs are hollow, cylindrical pieces

of metal having a wall thickness substantially equal to that of the body member. The legs 4 are welded to the part 2 of the bottom, as shown in figure 2.

There may be any desired number of legs 60 on the bottom, and they may be arranged in any suitable manner, but I prefer to arrange them substantially as shown in Figures 1 and 2, that is to say, with the legs in line with each other longitudinally and transversely of the bottom.

The annealing box is indicated by dotted lines 5 in Figure 2. The box may be of any suitable size and may be composed of any desirable material, but in order to get the 70 best results the same should be constructed of a material of substantially the same wall thickness as the bottom, and should be free from external projections and of uniform 75 wall thickness throughout.

By reason of the fact that the material of the bottom and that of the legs are of substantially the same chemical composition, both the bottom and legs have substantially equal expansion co-efficients, and therefore substantially the same amount of 80 expansion and contraction due to temperature changes. There is, therefore, little or no tendency for the legs to break away from the 85 bottom due to differences in expansion and contraction.

By having the wall thickness of the legs substantially the same as that of the bottom, the entire structure will be brought up to 90 temperature uniformly, thus avoiding the tendency to warp which would be present if there were differences in temperature throughout the structure. The location of the legs uniformly under the bottom prevents it from sagging and thereby obviates 95 any of the troubles such as usually result from sagging.

My invention has many advantages resulting from the construction and arrangement described, and by the use of which the material being treated is uniformly annealed 100 throughout the pack. The bottom has its mass uniformly distributed so that differences in temperature are avoided, as a result of which a more efficient and more durable bottom is secured.

While I have shown and described a specific embodiment of my invention, I am not to be limited to the exact arrangement described, as many changes may be made 110

therein without departing from the spirit of my invention, and scope of my broader claims. The drawings are illustrative only, and it will be obvious that the word "circular" as used herein may include elliptical and other generally circular shapes.

I claim:

1. An annealing bottom comprising a smooth, suitably shaped body and hollow legs thereon, said legs being of substantially the same chemical composition as that of the material of the body, substantially as described.

2. An annealing bottom comprising a suitably shaped body and hollow legs having a wall thickness substantially equal to that of the body, said legs being welded to said body and having substantially the same chemical composition as the body, substantially as described.

3. An annealing bottom comprising a suitably shaped body and cylindrical hollow legs having a wall thickness substantially equal to that of the body and being of

substantially the same chemical composition 25 as that of the body, welded to said body, substantially as described.

4. An annealing bottom comprising a suitably shaped body of substantially uniform wall thickness throughout and free from external projections, and hollow, cylindrical supporting legs on the bottom of said body, 30 said legs having a wall thickness substantially equal to that of the body and having substantially the same expansion and contraction as the body with given temperature changes, substantially as described.

5. An annealing bottom, comprising a suitably shaped body of substantially uniform wall thickness throughout, and hollow 40 supporting legs on said body, said legs having an expansion coefficient substantially equal to that of the body, substantially as described.

In testimony whereof I have hereunto set 45 my hand.

WAYNE RAWLEY.
